UNITED STATES PATENT OFFICE.

CICERO HINE, OF CHICAGO, ILLINOIS, ASSIGNOR TO BRUNSWICK-BALKE-COLLENDER COMPANY, OF CHICAGO, ILLINOIS, A CORPORATION OF DELAWARE.

DESIGN FOR A GAME-TABLE.

No. 40,092.

Specification for Design.

Patented June 22, 1909.

Application filed April 28, 1909. Serial No. 492,789. Term of patent 14 years.

To all whom it may concern:

Be it known that I, CICERO HINE, a subject of the King of Great Britain, residing at Chicago, in the county of Cook and State of Illinois, have invented a new, original, and ornamental Design for Game-Tables, of which the following is a specification, reference being had to the accompanying drawing, forming a part thereof.

In the drawing the figure is a perspective

view of a game table showing my new design.

I claim:

The ornamental design for a game table as shown.

CICERO HINE.
